UNITED STATES PATENT OFFICE.

FRANK C. SOPER, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,975, dated December 7, 1897.

Application filed November 1, 1897. Serial No. 657,102. Term of patent 14 years.

To all whom it may concern:

Be it known that I, FRANK C. SOPER, a citizen of the United States, residing at Chicago, in the county of Cook and State of Illinois, 5 have invented a certain new and original Design for Prism-Lights, of which the following is a specification.

My invention relates to designs for prism-lights.

10 Figure 1 is a plan view of a prism-light embodying my design. Fig. 2 is a cross-section therethrough.

15 A is the body of the prism-light; B, one side thereof; C C, a series of prisms on the opposite side, and D a series of lines crossing and interrupting the prisms and on the prism side arranged so as to form a figure or pattern.

The essential features of my design are found in a prism-light comprising a substantially flat and thin body with a series of prisms 20 on one side and a series of lines produced on the body of the prism-light on the prism side and crossing or interrupting the prisms, such lines arranged so as to form a figure or pattern.

25 I claim—

A design for a prism-light, substantially as shown and described.

FRANK C. SOPER.
